United States Patent Office

Des. 183,310
Patented Aug. 5, 1958

183,310

COMBINED BOTTLE AND CAP OR SIMILAR ARTICLE

Edward Hack, London, England, assignor to Flip Limited,
London, England

Application August 12, 1957, Serial No. 47,330

Term of patent 14 years

(Cl. D58—9)

FIG. 1

FIG. 4

Fig. 1 is a perspective view of a combined bottle and cap or similar article, showing my new design.

Fig. 2 is a top plan view thereof;

Fig. 3 is a side view in elevation thereof; and

Fig. 4 is an enlarged fragmentary detail thereof in elevation.

I claim:

The ornamental design for a combined bottle and cap or similar article, as shown.
